HANDBAG FRAME

George Laubenstein, Madison, N. J., assignor to
The J. E. Mergott Company, Newark, N. J., a
corporation of Delaware

Application June 15, 1938, Serial No. 213,742

2 Claims. (Cl. 150—29)

The present invention relates to handbags and more particularly to frames for such handbags and to constructions and methods of assembling such frames to form single or double handbags at the option of the handbag manufacturer.

In the manufacture of double handbags, such as handbags with inside purses, two frames are necessary, one for the outer main handbag and a second for the inner pocketbook or purse. Hitherto, two such frames have been made and assembled as unit structures by the frame manufacturer and then shipped to the handbag manufacturer for covering and completion of the bags. This procedure presents a number of practical difficulties. First of all, the assembled units are more difficult to pack and ship; secondly, the assembled units are frequently damaged in transit; and thirdly, the bag manufacturer may prefer at times to make single bags rather than double bags. If these frames, however, have been permanently assembled by the frame manufacturer, the bag manufacturer is unable to use such assembled frames for single bags even though the frames separately are otherwise adaptable for making such single bags. As a result, he is required to maintain a stock of frames suitable for making single bags having no pockets, and a separate stock of frames for making double bags having inside pockets or purses.

One of the objects of this invention is to eliminate the foregoing difficulties and to provide frame constructions which can be used for single or double bags at the option of the bag manufacturer. This is accomplished by having the frame manufacturer prepare separate frames and having him furnish the bag manufacturer separately with both outside frames and inside frames and special simple novel forms of connecting means whereby the frames may be quickly and easily assembled together without the use of tools at the bag manufacturer's option. The outside frames so furnished alone are capable of use for making single handbags and when an inner pocketbook frames are assembled therewith, double handbags may be made.

A further object of this invention is to provide novel inexpensive, efficient and quick means for attaching two frames together without tools which means will maintain the hinged members of the inner and outer frames together without permanent distortion of the frame members.

It is another object to provide methods of assembly without tools of such handbag frames for manufacturing double bags.

To the accomplishment of the foregoing and

such other objects as may hereinafter appear, this invention consists in the methods of assembly, construction, combination and arrangement of parts hereinafter described and then sought to be defined in the appended claims, reference being had to the accompanying drawings forming a part hereof and which shows, merely for the purpose of illustrative disclosure, several embodiments of my invention, it being expressly understood, however, that various changes may be made in practice within the scope of the claims without digressing from my inventive idea.

In the drawings in which similar reference characters denote corresponding parts:

Fig. 1 represents a perspective view of an outer handbag frame and an inner purse frame and associated parts embodying my invention assembled to form a double bag;

Fig. 2 represents a perspective view of the inner purse frame and the outer handbag frame prior to assembly and also illustrates the associated assembly parts unassembled used in connecting the two frames together;

Fig. 3 is an enlarged side elevational detail view, partially in vertical section at one end of two assembled frames adjacent the hinges thereof, showing the relationship of the said frames and the connecting parts when so assembled;

Fig. 4 is a side elevation of the construction of Fig. 3 viewed from the right;

Fig. 5 is a front elevation of inner purse and outer handbag frames of somewhat different construction in assembled relationship, illustrating a modified form of interconnecting means for assembling the outer frame with the inner frame;

Fig. 6 is a section on line 6—6 of Fig. 5;

Fig. 7 is a partial vertical section along line 7—7 of Fig. 5 viewed in the direction of the arrows;

Fig. 8 is a perspective view of leg portions of inner and outer frames illustrating a further modified means of assembling and connecting the frames together;

Fig. 9 is a partial front elevation of the two frames of Fig. 8 in assembled position;

Fig. 10 is a perspective view similar to that of Fig. 8, illustrating a further modified means of assembling two frames together; and

Fig. 11 is a front elevation, partially in vertical section of the assembled frames of Fig. 10.

Referring to the drawings, in Fig. 1 there is shown an outer or main handbag frame 10 and an inner or smaller purse frame 11, both of said

frames being substantially U-shaped. Such frames may be of standard construction. In the embodiment shown, outer frame 10 comprises two separate members 10¹ and 10² having channeled or tubular cross sections, each member being bent to substantially U shape. The legs 10³ and 10⁴ of said members are suitably hinged together, the lower ends of the said legs 10³ and 10⁴ of each of these members being provided respectively with ears 12 and 13, adjacent ears being adapted to overlap each other and to be pivotally connected together as by an eyelet or hollow rivet 14 or the like so that the two members 10¹ and 10² are hinged together and may be rotated toward or away from each other to close or open the bag.

The inner frame 11 similarly is shown as comprised of two U-shaped members 11¹ and 11² having channeled or tubular cross sections and whose legs 11³ and 11⁴ at their lower ends are provided with ears 15 and 16 respectively, adjacent ears being adapted to overlap each other and to be pivotally connected as by eyelets or hollow rivets 17 or the like so that the two members 11¹ and 11² are hinged together and may be rotated toward or away from each other to close or open the inner pocketbook or purse. The customary latching members 18 are provided on the inner frame members and, likewise, may if desired, be provided on the outer frame members.

As shown in Figs. 1 and 2, the inner frame 11 has substantially smaller overall dimensions than the outer frame 10 so that it will lie wholly within the completed outer bag when assembled with the outer frame.

For assembly purposes, I provide a group of assembly members for each end of the two frames. Each group may comprise a connecting or pivot pin member 19 which has at its opposite ends the reduced portions 20 and 21 whose diameters are so admeasured as to rotatably fit in and project through the openings 14' and 17' in the hollow rivets 14 and 17 of the respective outer and inner frames. These reduced portions form the shoulders 20' and 21' respectively with the main body of the pin member 19. Intermediate its ends the reduced portion 20 is provided with an annular groove or slot 22 which is so located as to lie on the side of the rivet 14 opposite that of the main body of the pin member 19 when the latter is in assembled position. A locking member or means in the form of a split ring 23 having a radial split or slot 23¹ or the like is provided which is adapted to be mounted on the reduced portion 20 in the slot or groove 22. When so mounted, it serves to lock the pin member 19 to the outer frame. The dimensions of the split or slot 23¹ in the ring 23 are somewhat less than the diameter of the pin member 19 in the groove 22 so that when the ring 23 is slid or forced into place in the said groove 22 against the normal spring action of the material of the ring or washer 23, which may be of metal or other suitable material, said spring action will prevent the ring from accidentally thereafter becoming disengaged and lost, and thereby serve to prevent accidental uncoupling of the member 19 from the frame 10 once it is attached thereto.

The reduced portion 21 likewise if desired may be provided with an annular groove or slot 24 (shown in dotted lines in Fig. 2) and a locking ring 23 mounted thereon.

In practice, frames 10 and 11 and the assem-

bly group members 19 and 23 are shipped unassembled to the handbag manufacturer by the frame manufacturer and the former either utilizes one or the other of the frames alone for single handbags or may assemble an outer and an inner frame for making a double handbag as follows:

The reduced portion 20 of a pin member 19 is inserted through openings 14' of each of the hinge members or hollow rivets 14 of the outer frame 10 until the annular groove 22 projects on the opposite side of the said rivets. Then a locking washer or ring 23 is forced into place in the annular groove and serves to lock the pin member 19 to the said outer frame. The outer frame 10 and the inner frame 11 are each then covered with the bag covering materials A and B indicated in Fig. 1. The covered inner frame is then mounted on the reduced portion 21 of the oppositely extending pin members 19 previously mounted on the outer frame by slightly and momentarily bowing or bending the inner frame legs 11³ and 11⁴ at opposite ends of the inner frame toward each other and allowing the said reduced portions 21 of the pin members 19 to slide into the openings 17' of the hollow rivets 17 of the said inner frame. Upon release of the inner frame legs by the operator, the natural resiliency of the said frame returns its legs to normal undeformed position so that the inner frame is now operatively connected to and mounted on the outer frame 10. If desired, to insure permanency of the connection, a locking ring 23 may now be forced into place in the annular groove 24 on the reduced portions 21 of the pin members 19 on the inside of the inner bag frame. Such auxiliary locking is optional. The two frames are now to all practical purposes permanently connected together and the double bag is ready for use.

The method and means described above are particularly advantageous in that no tools are required for assembly and no interference of any kind with the individual hinge action of the respective frames occurs. Furthermore, the connection between the two frames is entirely independent of the shape or structure of the bag frames themselves.

The embodiment shown in Figs. 5 to 7 inclusive is adapted more particularly for use with so-called inverted and rail top frames. Such frames like those of the first described modification may have the general U shape configuration shown in Fig. 5 and in addition have tubular or otherwise channel-shaped cross-section.

In these last-named figures, the outer frame 26 comprises the two hinged members 26¹ and 26². The lower ends of the legs 26³ and 26⁴ of each frame member are provided with bent or otherwise curved tubular ears 27 and 28 respectively, which are offset from the leg members into axial alinement, and the axially alined ears of each pair of legs pivotally joined together by a pinning member or rivet 29 or the like so that the two members 26¹ and 26² are hinged together and may be rotated towards or away from each other to close or open the bag.

As the members 26¹ and 26² are tubular, or channel-shaped, the bottoms or inner walls 26⁵ of each of a pair of legs of one of the said two members 26¹ and 26² substantially adjacent the hinge is provided with the openings or perforations 30 for a purpose to be presently described. Spring detent members 31 are suitably mounted as by spot welding or the like to the walls 26⁵

of frame member adjacent the said openings 30 and on the inner side of the frame member. These detent members 31 serve as a locking means as will be presently described.

The inner frame 11 is of the same or similar construction as that previously described in connection with Fig. 1, corresponding reference characters denoting like parts.

For assembly purposes, I provide connecting members for use in assembling and connecting each end of the inner frame to the outer frame 26. Each assembly member comprises a pivot pin 33 or the like which has projecting from one end the reduced portion 34 forming the shoulder 33' with the main body of the pin 33. At its opposite end, pin 33 is provided with a reduced portion 35 and an enlarged head 36 at its end. The head may be rounded as at 36¹ or otherwise suitably shaped to facilitate insertion into the openings 30 (which are somewhat larger in diameter than said head 36) against the action of spring detent member 31, permitting the end 31' of the latter to ride over and become engaged behind the head 36 in the reduced portion 35, thereby serving to lock said pin member 33 to the outer frame when its head is so inserted. If desired, a hole or aperture 37 may be provided in the frame to permit a suitable tool to be used to push the spring and release it.

As before, with this modification, the two frames 26 and 11 and the assembly pins 33 are shipped independently to the bag manufacturer. He, if desiring to make a double bag, inserts the head 36 of a pin member 33 in each of the openings 30 of the outer frame, the spring detent members 31 serving to lock it in place as hereinbefore described. Thereafter, the outer and inner frames 26 and 11 are covered independently with the required bag material. The covered inner frame is then mounted on the reduced portions 34 of the two oppositely extending pin members 33 previously mounted on the outer frame by slightly and momentarily bowing or bending the inner frame legs 11³ and 11⁴ inwardly and allowing the said reduced portion to slide into openings 17' of the hollow rivets 17 of the inner frame. Upon release by the operator, the natural resiliency of the said inner frame returns its legs to normal undeformed position so that the inner frame is now pivotally connected to the outer frame and its hinges slightly out of line with those of the outer frame. The length of the pin members 33 is so admeasured that the mounted inner frame is now substantially permanently connected to and assembled to the outer frame and the double bag is ready for use.

Locking rings similar to rings 23 of the first modification may be provided, if desired, and annular grooves (not shown) similar to grooves 24 provided in the reduced portions 34 of the pins 33 whereby such locking rings will serve to prevent accidental separation of the mounted inner frame from the outer frame. These locking rings, however, are optional, since the relative dimensions of pin members 33 and the two frames normally prevent accidental separation of the parts unless excessive inward bending strain is applied to the inner frame legs.

Various other means of mounting the assembly pin 33 to the outer frame may be employed.

For example, in Figs. 8 and 9 the outer frame legs 26⁴ of frame members 26² may be provided with the bayonet-type slot 38 formed in the inner face 26⁵ of the said frame legs. This slot 75

also is connected with an enlarged opening 38¹ in the side face 26⁶ of the said leg frame 26⁴ and its dimensions permit insertion of the head 36 of the pin 33 laterally into the said bayonet-type slot 38. In mounting the said pin, the head thereof is inserted through the opening 38¹, the reduced portion 36 of the pin moved laterally into the bayonet slot 38 and then vertically past the nose 38² of the said slot and then laterally so that the said reduced portion 36 engages behind the nose 38². With this embodiment, the individual frame members may be first covered with the requisite bag material. Thereafter, pivot pin or members 33 are attached to the inner frames 11 by inserting the reduced portions 34 thereof into the openings 17 of the hollow rivets 17 and fixing them in place in said rivets by upsetting the rear ends of said reduced portions at 34¹ in well-known manner. Thereafter, the legs of the inner frame are momentarily bent or bowed inwardly and heads 36 of the pins 33 inserted into bayonet-type slots 38 as hereinbefore described. The resiliency of the inner frame maintains said pins 33 locked in place in the said bayonet slots behind the noses 38² thereof. If desired, the pins 33 may be attached to the inner frames as described either by the frame manufacturer, or by the bag manufacturer prior to covering of either frame with bag-covering material.

In Figs. 10 and 11 a somewhat modified form of bayonet-type slot is shown provided in place of that of Figs. 8 and 9 which eliminates the necessity for the side opening 38¹ of the said Figs. 8 and 9. The curved slot 40 of this modification has a retaining nose 40¹ near its closed end and its open end 40² extends to the bottom end of the wall 26⁵ of the frame leg. The said wall end falls sufficiently short of the curved ear 27 to permit the head to be inserted behind the wall 26⁵ and to permit the reduced portion 36 to be moved in the slot 40 up to and behind the nose 40¹.

The method of assembling and connecting the inner to the outer frame is otherwise similar to that of the next previously described modifications.

It is understood, of course, that spring detent member 31 and opening 30 of Figs. 5-7 inclusive as well as the bayonet-type slots 38, etc., and 40 of Figs. 8 and 9, 10-11 respectively may be provided on the inner frames 11 instead of on the outer frames. In such case, the reduced portions 34 of the pin members would be mounted in the openings 29' of the rivets 29 rather than as now illustrated and the head 36 would be inserted into openings or bayonet-type slots in the inner frames as is well understood. In some instances, the frame for the inner purse may be composed of bars or parts of frame members, such as previously described. It is not necessary to use a whole frame for the inner purse.

The foregoing methods and means of carrying out my invention serve to provide savings in shipping costs and distribution costs and bag manufacturing costs; permit optional use by a bag manufacturer of outer frames independently of inner frames and vice versa; reduce requisite storage space at both the frame and bag manufacturers' plants; permit quick commercial and practicable assembly of double bag frames; and provide convenient and efficient methods and means of producing double or single handbags.

It is to be understood that I do not restrict myself to the exact methods and means described,

and that various other modifications and changes in method construction and shapes of parts may be made without departing from the spirit of my invention as defined in the appended claims.

I claim:

1. In combination, a double handbag comprising a hinged outer frame, a hinged inner frame and assembly members for attaching said frames together, at least one of said frames having channeled legs provided with openings in the bottom portions of the channels and spring leaf detent members each mounted by an end thereof to said channeled legs in said bottom portions thereof with their other ends each partially overlapping one of said openings, and said assembly members comprising pin members having reduced portions at opposite ends thereof and a headed portion at the end of one of reduced portions of each of said members, said headed portions being passed through said openings in said one of said frames engaged by said detent members to retain said pin members normally in permanent attachment with said one of said frames, the other reduced portion of each of said pin members being mounted in a hinge of the other of said two frames, said detent members being yieldable for disengagement

from the heads of said pin members for replacement purposes, and the said one of said frames having openings for the insertion of a tool for a releasing operation on said detent members.

5 2. As an article of manufacture, a frame for use in the manufacture of double handbags by the attachment thereto with assembly members of a second frame, said first-named frame comprising hinged channeled members, the legs of one of said channeled members being perforated in the bottom portions of the channels, and detent members mounted on said legs on said bottom portions adjacent the perforations and partially overlapping said perforations, said detent members serving for removably engaging and normally retaining headed portions of said assembly members adapted to be inserted in said perforations whereby the two frames may be connected together, and said bottom portions of the channels having additional perforations lying between those first mentioned and the mounted portions of said members for the insertion of a tool to disengage said detent members from said assembly members.
